UNITED STATES PATENT OFFICE.

JULIUS M. ERNST, OF BROOKLYN, NEW YORK.

FOLDING STEP FOR SUBWAY-CARS.

No. 919,333.

Specification of Letters Patent. Patented April 27, 1909.

Application filed May 10, 1907. Serial No. 372,931.

To all whom it may concern:

Be it known that I, JULIUS M. ERNST, a citizen of the United States, residing at Brooklyn, in the county of Kings and State 5 of New York, have invented a new and useful Improvement in Folding Steps for Subway-Cars, of which the following is a specification.

This invention relates to car attachments, 10 and more particularly to platform tread plate attachments adapted to be used in connection with the door operating mechanism now in use in subway cars, so that the space between the car platform and station-platform will be closed when the door is opened so that all danger of passengers slipping into the space between the platform is prevented when getting on or off a car.

Another object of my invention is to provide a curved tread-plate so that it will adjust itself to different height platforms.

Another object of my invention is to so construct the ends of the tread plate operating links by a spring equalizer so that the plates will give if they come down on a person's foot on the platform.

With these and other objects in view, the invention consists in the novel features of construction, combination and arrangement 30 of parts hereinafter fully described and pointed out in the claims.

In the drawings forming a part of this specification:—Figure 1 is a side view of a portion of a car showing my improved tread-plate attached to the car. Fig. 2 is a horizontal sectional view showing the tread-plate lowered in position to be used. Fig. 3 is an end view of a car in a subway showing one of the tread-plates dropped on the station-platform. Fig. 4 is a plan view of the tread-plate. Fig. 5 is a sectional view of the tread-plate. Fig. 6 is a side view of my improved equalizer shewing the links broken off. Fig. 7 is a longitudinal sectional view of the same. Fig. 8 is a section taken on lines 8—8 of Fig. 7. Fig. 9 is a section taken on lines 9—9 of Fig. 7.

Referring to the drawings A indicates an ordinary vestibule car provided with the 50 usual side door and end doorways. Pivotally mounted on each side of the end-doorway is a hand lever B, to which is connected a lever C connected to the crank-arm C' of a

double crank C to the other arm C² of which is connected a link C³. Connected to the 55 end of the link is a bell crank lever C⁴ horizontally disposed under the hood of the car. The bell crank is connected to a link C⁵ which is connected to an operating lever C⁶ which is pivotally connected at one end to a slide C⁸ 60 mounted in a transverse guideway and at the other end to a door for operating the same all of which are of the ordinary construction of door operating mechanism now in use on subway cars.

Mounted in the sides of the frames of the side-doorways adjacent the car platform, are shafts D which extend forwardly through the front of the car and are provided with crank-arms D' at their ends which are connected to the hand-lever B by links E, E', which are connected together by an equalizer G. The equalizer is formed in a casing G' having a threaded bore formed in the closed ends, through which works the threaded 70 end of the link E which is adjustably secured thereon by a set-nut H, so that the length of the rod can be adjusted to suit different heights of platforms. The other end of the casing is opened and externally threaded on 75 which is secured an internally threaded hexagonal cap I by a set screw 12 and provided with a bearing sleeve I' through which works the end of the link E' on which are secured sleeves J adjacent their ends by set-screws 80 85 J'. A coiled spring K surrounds the links E' between the head and cap for holding the plate away from the door until it is completely closed.

Arranged in the casing between the closed 90 end and sleeve of the link E is a coiled spring L so as to prevent the plate from injuring a person's foot who might be standing near the edge of the platform if it came down on it.

Secured on the shafts D in the side doorway are the sleeves F' of a curved tread-plate F provided with a rubber covering F² on their top, and rubber buffers F³ adjacent their outer ends adapted to rest on the platform when the tread-plates are lowered. The sleeves F' are provided with set-screws F⁴ adapted to engage the shafts and securely lock the tread-plates in the desired position on the shaft.

From the foregoing description it will be

readily seen that when the hand levers are operated, the tread-plates will drop on the station platform without any noise.

Having thus fully described my invention, 5 what I claim as new and desire to secure by Letters Patent is:-

1. The combination with a railroad car provided with sliding doors, and hand levers and means connected to said hand levers for 10 operating said doors, of curved tread-plates mounted in the doorway above the platform of the cars, and yieldable links connecting said plates to the hand-levers.

2. The combination with a railroad car 15 provided with sliding side-doors and hand levers, and means connected to said levers for operating said doors, of shafts mounted in said doorways adjacent the car platform provided with crank-arms, curved tread-plates secured on said shaft in said doorways and yieldable links connecting said crank-arms to the hand-levers for the purpose described.

3. The combination with a railroad car 25 provided with sliding doors and hand-levers and means connected to said hand levers for operating said doors, of shafts mounted in said doorways adjacent said platform provided with crank-arms, of curved plates provided with sleeves mounted on said shafts, set-screws mounted in said sleeves adapted to engage said shaft, a rubber covering secured over the top of said plates, rubber buffers secured under the end of said plates 30 and links connecting said crank-arms to the hand-levers.

4. The combination with a railroad car provided with sliding doors and hand levers, and means connected to said hand levers for 40 operating said doors, of curved tread-plates mounted in the doorway and links connected together by spring equalizers, connecting said plates to the hand levers.

5. The combination with a railroad car 45 provided with sliding doors and hand levers, and means connected to said hand levers for operating said doors, of tread-plates mounted in the doorway, links connected to said hand-levers adjustably mounted in a casing 50 and links connected to said plates slidably

mounted in said casing provided with a sleeve and springs arranged in said casing to each side of said sleeve.

6. The combination with a railroad car 55 provided with sliding doors, and hand levers and means connected to said hand levers, for operating said doors, of shafts mounted in said doorways provided with crank arms, tread-plates secured on said shafts, links connected to said hand levers provided with 60 threaded ends adjustably mounted in casings provided with caps at their ends, links connected to said crank arms, of the shaft having sleeves at their ends slidably mounted in said casing, central springs surrounding 65 said links, said caps and sleeves, and coiled springs arranged in said casings between said sleeves and closed ends.

7. The combination with a car provided 70 with sliding side doors, of hand-levers, means connected to said hand-levers for operating said doors, shafts mounted in the doorways adjacent the car platform provided with crank-arms, curved plates carried by said shafts, links connected to said crank-arms, 75 casings adjustably connected to said links, links slidably mounted in said casings connected to said hand-levers and springs surrounding said links within said casings.

8. The combination with a car, of shafts 80 mounted in the doorways of the car adjacent the car-platform, curved plates carried by said shafts, links connected to said crank-arms provided with threaded ends, casings 85 provided with closed ends having threaded bores secured over the threaded ends of said links provided with bearing caps, sleeves secured over the open ends of said casings, links mounted in said bearing sleeves, sleeves secured over the ends of said 90 links, coiled springs surrounding said links, coiled springs arranged in said casings between the closed ends and links, and hand-levers connected to the free ends of the links with the sleeves for the purpose described.
